UNITED STATES PATENT OFFICE.

FRANCIS J. EVANS, OF BURBANK, WASHINGTON.

PUMP.

1,322,552.

Specification of Letters Patent. Patented Nov. 25, 1919.

Application filed April 8, 1919. Serial No. 288,475

To all whom it may concern:

Be it known that I, FRANCIS J. EVANS, a citizen of the United States, residing at Burbank, in the county of Walla Walla and State of Washington, have invented certain new and useful Improvements in Pumps, of which the following is a specification.

My present invention relates to improvements in pumps of that type employing 10 valved pistons or plungers, with means for reciprocating the piston, and the pump is especially adapted, by the employment of an auxiliary or additional valve mechanism, for use in irrigation work where the water 15 to be pumped is usually accompanied by the presence of sand, soil weeds and other foreign matters.

The primary object of the invention is the provision of a pumping mechanism especially adapted to overcome the difficulties 20 of these conditions by constituting the valve device automatically self-cleaning, and the valve of the piston self-seating notwithstanding the presence of foreign matters in 25 the valve seat of the piston or plunger of the pump, and further, by the use of the auxiliary or gate valve, when not in use, all foreign matters are excluded from the valve of the piston thus preventing clogging 30 of the parts. In addition the pumping mechanism is compactly arranged, durable, and efficient in the operation of lifting the column of water to be disposed as desired.

In the accompanying drawings I have 35 illustrated one complete example of the physical embodiment of my invention constructed and arranged according to the best mode I have so far devised for the practical application of the principles of my invention, and while I have referred to the pump 40 as designed especially for overcoming the difficulties attendant upon the pumping operations in irrigation, it will readily be apparent that the mechanism is equally applicable for other numerous uses.

Figure 1 is a view in elevation of the pumping mechanism, parts being broken away for convenience of illustration.

Fig. 2 is an enlarged, sectional, detail 50 view at the lower end of the pump cylinder showing the piston valve and the gate valves both in section.

Fig. 3 is a view at the pump head.

Fig. 4 is a detail view showing the auxiliary pump valve lever and connections.

Fig. 5 is an edge view of the auxiliary

valve lever showing also the main piston-valve link in section.

As illustrated in the drawings, the preferred form of the invention involves the use of a comparatively large cylinder 1 approximately eight, ten, or twelve inches in diameter and of suitable or required length and provided with the usual spout at the T-coupling 1^a, through which the water is to be lifted by the reciprocating, valved piston 2, operating near the lower end of the cylinder, which of course is placed in the river, well, or other place from which water is to be pumped.

The valved piston is of special construction and comprises a metallic barrel 3 about which are clamped a sufficient number of packing rings or gaskets 4, the clamping nut 5 serving to hold the gaskets or rings 75 between it and the flange 6 of the barrel, and at the lower end of the valved piston is secured the valve seat 2' of conical form or tapering upwardly, to receive the valve 7 of the piston. It will be noted that the valve is of truncated cone shape, with the larger end below, and fits snugly up into its seat 2' as shown in Fig. 2, when pulled therein by its stem 8 to which it is attached in usual manner. The valve of the piston 80 is related thereto in such manner that an initial movement of the valve is permitted, before the piston *per se* is moved, and therefore a stop bar or limit bar 9 is threaded on the stem, or is fitted over the threaded 85 stem and secured thereon by the upper and lower clamping nuts 10 10 on the threaded stem, and this bar engages and presses on the upper open end 11 of the barrel 3 of the piston or plunger 2.

At its upper end the cylinder is provided with the usual screw cap 12 and packing nut 13, for the plunger rod or stem 8, and the latter is operated, either by mechanical power, or manually, but preferably the former, as here illustrated, when the beam or pump lever 14 is actuated. This beam or lever has a suitable fulcrum, and is connected to the plunger or piston rod through the instrumentality of the link 15 formed by two straps as shown and pivoted to the stem at 16 and to the lever at 16'.

The operation of the valved piston will be apparent from an inspection of the drawings, and it will suffice to say that as the piston descends the valve plug 7 is open from its seat and the limit bar

9 is seated at the top of the barrel of the piston, then on the up stroke of the stem and its piston the plug closes the valve seat at the lower end, and the water is lifted 5 through the chamber or barrel of the piston and so up through the cylinder.

The tapered construction of the valve plug and the complementary formation of the valve seat insures an automatic and correct seating of the valve plug, and the foreign matter, such as sand, gravel, soil, or other sediment at the bottom of the river entering through the valve seat will be retained in the barrel of the piston and forced 15 out on the next downward stroke of the pump, the plug being in open position to permit the egress of foreign matter, thus preventing clogging of parts with consequent difficulties.

20 In conjunction with the reciprocating valved piston or plunger I utilize a gate valve 17 to close the lower end or inlet end of the cylinder 1, on the down stroke of the piston the valve being hinged at 18 to the 25 cylinder, to swing from closed to open position and vice versa in proper and predetermined co-action with the movement of the piston or plunger 2 within the cylinder.

The valve 17 is manipulated through the 30 action of the piston actuating mechanism and therefore is provided with a connecting rod 19 and actuating lever 20 the latter being governed and operated by the movement of the piston link 15 as it reciprocates vertically with the movement of the piston. The lever 20 is supported on the bracket 21 fixed in suitable manner to the cylinder or cylinder head 12 and to compensate for an oscillation on the part of the link 15 in its 35 movement, the lever is slotted for its fulcrum support or pivot 22, the slot being indicated at 23, and 24 is a spring connected at one end of the lever and attached to the bracket 21, with a tendency to pull on the 45 lever and permit the gate valve to swing open. But the gate valve is directly operated by engagement of the lever and link through the roller 25 on the end of the lever 20, the end of the lever with its roller projecting between the two straps of the link 15, the anti-friction roller 26 between the two straps of the link, and the abutments or stops 27 that project from opposite sides of the lever and prevent its undesired projection through the link.

The co-action between the piston link and the actuating lever for the gate valve is illustrated in full and dotted lines in the drawing, and it should be understood that 50 although the piston valve and gate valve operate synchronously, they do not open and close simultaneously. The gate valve is not opened until the piston has reached nearly the end of its down stroke and is near 55 the bottom of the cylinder or chamber.

When however, the lever 20 is released the spring immediately pulls the short or outer arm of the lever to position with the longer or free arm at about right angles to the link, thus opening the gate valve at about 70 the time the lost motion is completed on the up or working stroke of the piston. At this time the rollers 27 traveling along the edges of the link straps cause the lever to be swung to extreme outward position, as 75 in dotted lines Fig. 1 thus elongating the outer or shorter arm of the lever and giving it longer sweeping motion, so that as soon as the lost motion is completed in the down stroke the link strikes the lever with 80 a comparatively longer arm to close the gate and a shorter arm to swing the lever, thus quickly opening the gate for the ingress of water as the piston rises. The slot 23 in the lever permits this change of leverage 85 by which the quick, but delayed, action of the closing of the gate valve is accomplished, and the slot structure also permits the proper movement of the free end of the lever in its relation to the link so that when the 90 gate valve is closed the lever is so arranged and operable that the extremely short arm as in Fig. 1 provides a short leverage for the closing movement of the gate valve, and no more, while the inner or free end of the 95 lever, because of the slot, is made an extremely long arm and moves with the link to the extremity of the down stroke.

Preferably anti-friction rollers, or a roller, is provided at the movable fulcrum 100 point of the lever, traveling in the slot and accommodating all the angles of the lever in its movement. The roller 25 travels between the two straps of the link, and acts as a hook to engage the roller 26 (see Fig. 105 4), until the former reaches a point on the down stroke of the link when the rollers disengage and permit the spring 24 to pull down on the outer, short arm of the lever to open the gate valve.

110 When the link is on the up or working stroke, the roller 26 is on the lower side of the lever until the former rolls around the roller 25 at the extreme end of the up-stroke, and is in position to be depressed on the 115 down stroke.

What I claim is—

1. The combination in a pump with its cylinder and reciprocating valved piston, of a hinged valve at the lower end of the cylinder, and actuating mechanism controlled by the movement of the piston for opening the hinged valve on the up stroke of the piston and closing said valve on the down stroke of the piston.

120 2. The combination of a pump with its cylinder and reciprocating valved piston, of a hinged valve at the lower end of the cylinder, a shiftable lever and connections controlled by the movement of the piston for 125 130

opening and closing said hinged valve as described.

3. The combination in a reciprocating pump with a reciprocating link, of a hinged valve, a slotted shiftable spring pressed lever and a valve rod connecting said lever and hinged valve, the free end of the lever engaging said link for controlling the opening and closing of the hinged valve.

10 4. The combination in a reciprocating

pump with a reciprocating link, of a hinged valve, a slotted, shiftable, spring pressed lever and a rod connecting said lever and hinged valve, anti-friction rollers on the lever and link and said lever adapted to 15 engage the link to hold the hinged valve closed, and to be released therefrom for opening the hinged valve.

In testimony whereof I affix my signature.

FRANCIS J. EVANS.
